UNITED STATES PATENT OFFICE

HEYMAN ROSENBERG, OF NEW YORK, N. Y.

APPARATUS FOR AND ART OF TREATMENT OF METAL WORK

Application filed June 20, 1929. Serial No. 372,457.

This invention relates to improvements in the art of and apparatus for heat treating, and particularly case-hardening work, and more especially work comprising a series of 5 small parts, such as screws, nails, bolts, nuts, buckles, small tools, and the like.

A number of important objects are attained by the present invention which will best be understood by comparison with the most 10 popular method and apparatus now in use for case-hardening purposes.

It is, of course, well known that cyanide may be effectively used for case-hardening purposes, and other salts are also commonly 15 employed, but, for facility, convenience, and brevity of discussion, cyanide will be particularly referred to herein with the reservation, however, that any other available salt may be utilized accompanied by the varying 20 and limiting conditions incident to the known qualifications of substitute salts.

It is common practice to provide a vat heated by an appropriate furnace, such as a gas furnace, and supplied with cyanide, or 25 other required salts, and raised to the temperature of liquefaction. The article or articles to be case-hardened are then lowered into the liquid cyanide and allowed to remain until the required temperature is attained. The article or articles are then lifted 30 from the cyanide bath and quenched in water or other appropriate quenching fluid. The common mode of carrying out this practice has been to place the articles to be hardened in a metallic basket or reticulated container having a long handle. The handle enables the operator to stand at some distance from the vat which is located over the furnace, but in doing so the operator is required to sustain the unbalanced load at a 35 tremendously disadvantageous leverage incident to the length of the handle. This load is manually lowered into the molten cyanide, and when the required temperature has been 40 reached, as indicated by the commonly used electrical pyrometer, the operator grasps the handle and at the expenditure of very substantial energy lifts the basket of work from the vat, removes it from above the furnace, 45 and empties it into a vat of quenching fluid.

It is common practice to hood the furnace and cyanide vat and vent the hood and also to provide effective general ventilation for the room or space in which the furnace is located, but the quenching vat must necessarily be spaced from the furnace and the load of heated work must be withdrawn from the hood, carried to the water, and discharged. Fumes of the cyanide inevitably 55 escape into the air and drippings of cyanide fall onto the floor of the room, and the operator is injured by the condition of the air before the ventilating system can effectively dispose of the fumes. Furthermore, the cyanide on the floor becomes slippery and 60 renders labor the more difficult. When dry on the floor, the cyanide is removed therefrom with difficulty and creates a cyanide dust which is injurious.

Under these conditions, the labor problem 70 becomes an important factor both because it is not always easy to get men possessing sufficient physical strength and endurance to undertake the labor, and it is imperative that a change be made frequently if cyanide 75 poisoning of the operator is to be prevented, so that rotation of laborers tends toward lack of efficiency, since each new man must be trained in his task. Furthermore, the operator some times receives a burn from a 80 drop of cyanide which is liable to produce a quite serious condition, and at other times when the door to the hood is open and the operator withdraws the basket, he is momentarily choked by the fumes, and stopping to catch his breath holds the basket in the air and thus allows a certain amount of cooling of the work, which proportionally decreases the efficacy of hardening incident 85 to quenching. These are a few of the difficulties and problems, of which there are many others, in the art of cyanide case-hardening, all of which are overcome by the present invention.

Among the various objects in view, the present invention provides the following:

(1) Avoidance of undue exposure of the work to air before quenching, and thus affords a uniform and even penetration.

(2) Direct hooded ventilation for the fur-

nace, the molten cyanide, and the quenching tank, whereby escape of cyanide fumes to the air being breathed by the operator is avoided.

5 (3) Prevention of waste of cyanide and the return of all cyanide drippings to the furnace pot or vat.

(4) Saving of time and expense in enabling one operator to care for a series of furnaces, whereas the present known methods require at least one operator for each furnace.

(5) Very substantial reduction in labor required, so that the operator does not become exhausted and his efficiency reduced as the day progresses, which is known to occur in the old method of cyanide case-hardening.

(6) Uniform efficiency in the operation of all furnaces and in the product from each.

20 (7) Avoidance of cyanide or water from dripping or splashing onto the floor, avoidance of water splashing into or otherwise reaching the cyanide vat, and avoidance of burns by cyanide or hot water.

25 (8) Substantial saving of floor space.

(9) Substantial saving of equipment and particularly of the work containers or baskets which, under the old method of manual handling, became dented, bent, and so injured by impact as to be destroyed beyond capacity for further use in a comparative short time; whereas by the present invention the basket is never thus injured, and under the present invention a basket will last many times longer than a basket under the old method. The saving of wear and tear on the basket is so great that under the new method a basket will frequently outlast the basket of the old method fifty times or more.

40 (10) Substantial saving in every direction and particularly and especially in time, as the operation is uniform and never interrupted by mishaps such as occur when manual handling is required.

25 With these and other objects in view as
will in part hereinafter become apparent and
in part be stated, the invention comprises
both the method of handling and the con-
structions, combinations, and arrangements of
59 parts for handling as subsequently specified
and thereafter particularly pointed out in
the appended claims.

In the accompanying drawings,—

Figure 1 is a view in side elevation of apparatus embodying the features of the present invention, parts being broken away and parts seen in section.

Figure 2 is a top plan view of the parts seen in Figure 1 with the hoods omitted.

69 Figure 3 is a fragmentary, vertical section through the basket-carrying plate and contiguous parts, parts being seen in elevation, and the section being taken approximately on the plane indicated by line 3—3 of Figure 2.

Figure 4 is a fragmentary end view of the same.

Figure 5 is a detailed, sectional elevation of a modified form of gearing.

Figure 6 is a vertical section taken on the plane indicated by line 6-6 of Figure 1, and looking toward the furnace.

Figure 7 is a horizontal section taken approximately on the plane indicated by line 7-7 of Figure 1, and looking upward. 73

Figure 8 is a fragmentary, sectional elevation of a modified mounting for the thermocouple.

Referring to the drawings by numerals,

1 indicates any appropriate furnace housing adapted for the use of any acceptable fuel, whether solid, liquid or gaseous. Gas burners are popular and preferred for various reasons where available and economical, but, of course, any other source of heat may be provided for the furnace 1. The furnace 1 consists essentially of a housing mounted on legs or supports 2 and covered by a plate 3, the plate resting on appropriate portions of the angle iron or other suitable framing of housing 1. Mounted on the plate 3 is a table 4 provided with a pendent flange 5 surrounding the housing 1. Clamping bolts 6 anchor the plate to lower portions of housing 1. The table 4 is provided with an upstanding flange 7, preferably of substantially rectangular form. Table 4 is preferably provided with an edgewise extending projection 9, apertured at 8, to receive the hereinafter mentioned thermocouple as a supporting bracket therefor when the thermocouple is not in use. The plate 3 is apertured centrally and table 4 is provided with an annular, pendent flange 10 snugly fitting in the central aperture of plate 3, the table 4 being centrally open within and bordered by flange 10. A furnace pot or vat 11 extends through the central aperture of table 4 and is supported on the table by a laterally extending annular flange 12. The pot or vat 11 regularly contains the cyanide or other salts. In cyaniding and like case-hardening, it is customary to determine with precision the attainment of the requisite temperature by employing an appropriate pyrometer whose thermocouple 13 is arranged with its thermo-sensitive resistance within the pot 11 and provided with a circuit 14 of common and well known construction.

For facility of relative reference, it may be considered that that side of the apparatus seen in Figure 1 is the front of the apparatus. The table 4 at its right side extends beyond furnace 1 and is provided with pendent portions 15, seen best in Figure 4, which are perforated and provide bearings for a shaft 16. Shaft 16 extends beyond the rear face of the apparatus and is there engaged by an adjustable counterbalance arm and weight 17. The forward end portion of shaft 16 projects beyond the table 4 and carries a spur 130

gear 18 meshing with a pinion 19 fixed to a jack shaft 20. The shaft 20 is journaled in an enlargement of flange 5 and in a pendent flange from a bracket 21 preferably formed integral with the table 4. An appropriate housing 22 encloses the gearing 18 and 19, and an operating handle 23, or other appropriate power means, is fixed to the shaft 20 to enable rotation or oscillation of shaft 16. Fixed to the shaft 16 and extending across one portion of the table 4 and covering the vat or furnace pot 11, during the heating operation, is a crank arm 24. The crank arm 24 is preferably in the form of a rectangular plate, but may, of course, be a framework or merely spaced bars appropriately connected, as hereinafter indicated. The plate making up the crank arm 24 is provided with pendent ears 25 surrounding the shaft 16 and anchored thereto by cross pins 26 penetrating said ears and shaft. Thus, when the shaft 20 is rotated, the plate 24 will be swung about and with the shaft 16. The plate 24 is preferably provided with longitudinal, marginal flanges 27, 27, terminating at the ends of the plate. Near the free end of the plate 24 an aperture 28 is provided to permit the passage of a basket 29. The basket 29 is, of course, capable of a wide range of variation in form and construction, but preferably consists of a reticulated receptacle adapted to withstand the action to which it is subjected. The body of the basket 29 is sustained by straps of appropriate dimensions and stability, some of which extend upwardly through the aperture 28 and are formed with overlying flaps, tabs, or end portions 30, each bolted, riveted, or otherwise appropriately fixed at 31 to the plate or crank arm 24. The parts are so located with respect to each other that when the plate or crank arm 24 is in its lowermost position above the table 4, the basket 29 will be extended within and preferably centrally of the vat or pot 11, so that the metal work comprising the contents of the basket 29 will be subjected to the action of the molten contents of the vat.

A quenching tank 32 is arranged at one side of the furnace 1, and preferably spaced an appreciable distance below the level of the crank arm or plate 24 when the same is in position with the basket 29 in vat 11. The spacing should be sufficient to insure against splashing of the quenching liquid from tank 32 over to vat 11. The quenching liquid will ordinarily be water, but may, of course, be oil or any other acceptable quenching fluid. Arranged within the tank 2 is a reticulated tray 33, which is preferably formed on a continuous curve so as to be arcuate in longitudinal cross section, as indicated in Figure 1, whereby effective discharge is assured. The tray 33 may be constructed in any of various ways, but preferably consists of a perforated

sheet metal housing engaged by a series of straps 34, 34, each extending to and fixed to an actuating shaft 35. The straps 34 may be secured by pins 36, or in any other acceptable fashion, to the shaft 35 to insure movement of the tray 33 incident to rocking of the shaft 35. An adjustable counterbalance 37 is provided for shaft 35, and an operating crank 38, or other appropriate power means, is also fixed to the shaft 35. A shaft 35 is arranged adjacent that end of tray 33 remote from the furnace housing 1, and the free end of the tray 33 is adapted to rest on an appropriate support 39 within the tank 32 when the tray 33 is in its work-receiving position. Appropriate straps 40, 40 are fixed to the sides of the tray 33 and upstand therefrom and carry a cross bar 41 positioned to be struck by and interrupt the movement of the basket carrying crank arm 24 during the discharge movement of the basket when the parts reach the discharging position seen in dotted lines in Figure 1.

At the right of the tank 32 is arranged an appropriate framework 42 supporting a hopper 43. A cross bar 44 is preferably carried by the hopper 43 to interrupt movement of tray 33 as it reaches its complete, discharging position, shown in dotted lines in Figure 1. An appropriate receptacle, such as a perforated metal kettle 45, is preferably manually placed to receive the discharge from the hopper 43, and it will be understood, of course, that the work received by the kettle 45 will be manually removed, preferably by removing the kettle and replacing another as soon as one is filled. Obviously, an endless conveyor or other suitable conveying means may be employed for transferring the discharge from hopper 43 to the place of further treatment.

Arranged above the furnace housing 1 is a hood 46 converging to an appropriate flue or vent 47, the hood 46 being constructed to snugly fit the outer surface of the flange 7 to prevent leakage of fumes. The flange 7, as best seen in Figure 2, is continuous except where interrupted to accommodate the plate 24, and the hood 46 is similarly continuous except for a doorway to accommodate the swing of the plate 24 and its connected parts. Snugly fitting the upper portion of and closing the tank 32 is a hood 48 converging at its upper portion to a flue or other appropriate exhaust 49. The hood 48 includes also a closing sheet 50 between the tank 32 and the furnace housing 1, and the hood 48 is provided with a doorway similar to that formed in hood 46 to accommodate the swing of the plate 24 and its connected parts, as indicated in dotted lines in Figure 1. A vestibule hood 51 surrounds the said doorways and encloses the space therebetween so as to provide a sealed housing for all the area above and between the furnace and the quenching vat or

5 tank. The left or exposed face of the hood 48 is also closed by an appropriate wall, but a portion of the wall is formed into a freely 10 vertically swinging door 52 adapted to swing outward as indicated in dotted lines in Figure 1 to allow the tray 33 to move to the discharging position and thereafter to swing inward as indicated by the arc shown in dot and dash lines in Figure 1 to permit the tray 33 to 15 return to the work-receiving position. Obviously, the door 52 will normally remain at rest in a vertical position sealing the hood and preventing exhaustion of fumes otherwise than through the flues 47 and 48.

15 It should be understood that work may be supplied to the basket 29, when the latter is within the vat 11, by an appropriately arranged self-sealing discharge or caisson-like lock for admitting work without permitting 20 exhaust of fumes, and that the work may be preheated within such lock from exhaust heat of furnace 1, all of which is illustrated in detail in my companion, co-pending application, and, therefore, not shown specifically 25 herein. Likewise, it is entirely feasible to make the operations completely automatic by providing electric motors for actuating the shafts 16 and 35 successively in properly timed sequence and subject to the automatic 30 control of electrical switch-closing devices governed by the condition of the pyrometer circuit or the apparatus actuated thereby, all as specifically disclosed in my said companion, co-pending application.

35 It is preferable to employ means for delivering work to the basket 29 without affording an opportunity for exhaustion of fumes, but a supply may be delivered to the basket 29 at an extreme minimum of risk of 40 impregnation of air by providing a door 53 in the hood 46 which may be partly opened and the commonly used elongated scoop passed into position for delivering a charge 45 of work to the basket 29, whereupon the scoop is withdrawn and the door 53 closed. Door 53, of course, will be maintained closed at all other times and at all times during operation when the sealing lock is utilized as above indicated. Door 53 is preferably provided with a pyrex plate 54, or other appropriate heat-resisting, transparent sheet. A door 55 is also preferably provided for the hood 48 and the transparent sheet 56 similar to sheet 54 is arranged in door 55. The sheets 55 54 and 56 enable the operator to observe conditions within the respective hoods and the doors 54 and 55 are employed chiefly or wholly for access to the interior of the hoods when the apparatus is not in operation and 60 the furnace 1 is not heated. The doors 55 are provided with any appropriate locks 57 for normally retaining them closed, but, of course, either door may be opened for emergency access to the interior of the hoods.

65 In the carrying out of the improved art by

the improved apparatus above described, a quantity of cyanide or other salts is supplied in solidified form to the pot or vat 11, and the furnace 1 started, as by the lighting of the gas burner or burners, or other fuel. Basket 29 will be held in a partly raised position 70 while the cyanide is being heated, and as soon as the cyanide has become molten, the basket may be lowered into the bath in vat 11, and a supply of work will then be delivered into 75 the basket. The cyanide will melt at about 800° F., while the melting point of other salts varies from 600° to 1000° F. When the cyanide has attained the required temperature, ranging from 1400° F. to 1600° F., according to the work being treated, the work 80 is in condition for removal. The work is left in the bath until the pyrometer reading indicates the attaining of the requisite temperature, and then the operator rotates the shaft 85 10, by actuating the handles or levers 23, and thus elevates the basket 29 by swinging the crank arm 24 upward. When the basket has reached a point above the liquid level in vat 90 2, the operator holds the parts in this position until the adhering molten cyanide drips back into the vat. The operator then continues his rotation of shaft 20 to cause the basket 29 to be swung to the inverted position indicated in dotted lines in Figure 1. Most, and usually all, of the work will at once fall from the basket into the quenching vat. If any particular piece of work should, for any reason, remain in the basket, as by being lodged partially in one of the openings of the basket 100 wall, dislodgment may be effected by oscillating shaft 20 and causing the basket to gently tap the cross rod 41. The operator then reverses the rotation of shaft 20 and swings the basket 29 back to a position above 105 the vat 11. It is preferable to lower the basket into vat 11 before a fresh charge of work is delivered to the basket. The introduction of the charge of fresh work is either accomplished through the sealed lock, not illustrated herein, but shown in the above referred to companion, co-pending application, or may be delivered by the use of a long scoop 110 through the doorway closed by door 53. The introduction of the fresh supply of work reduces the temperature of the liquid in vat 11, and the operator must, therefore, wait until the pyrometer indicates the re-attainment of the required high degree of temperature by the contents of vat 11 before again lifting 115 the basket 29 out of the vat.

120 While thus waiting for the rise in temperature, the operator will rotate the crank 38 for rocking the shaft 35 from the position seen in full lines in Figure 1 to the position of discharge seen at the righthand of Figure 2 in dotted lines. As the tray 33 is elevated incident to this rocking of shaft 35, the door or gate 52 will be swung outward by the contact 125 of parts of tray 33 therewith and part of the 130

work within tray 33 will begin to roll down into the hopper 43. The discharge will continue as the tray 33 approaches its outermost position, and if any parts of the work have 5 become caught or otherwise fail to discharge, the tapping of the tray against the cross bar 44 by gentle oscillation of shaft 35 will effect complete discharge. Meanwhile, the gate 52 will have swung back and the operator will 10 then reverse the movement of shaft 35 and return tray 33 to its position within vat 32. Gate 52 will swing inward out of the path of tray 33 to permit the tray to move to its innermost position, and then the gate will swing 15 automatically by gravity back to its pendent, closed position. The parts are then ready for a repetition of the cycle of operation as just stated. Meanwhile, it will be observed that no opportunity is afforded for the fumes to 20 escape into the surrounding atmosphere during any part of the time when fumes are liable to escape. It will also be observed that ample opportunity is afforded for the drain back of cyanide, and that no loss or detrimental results occur from cyanide dripping from the basket of work. Also, the falling of the work in the quenching bath does not produce the 25 harmful results of getting moisture into the cyanide bath. The quenching bath is purposely set at a point sufficiently below the level of the open upper end of the cyanide vat to insure against splashing of water into the latter, and any water which may be splashed onto the plate 24 or parts carried thereby will 30 drain back into the vat 32 or be evaporated in the course of the upward movement of basket 29 during the return movement of plate 24.

The gears 18 and 19 while shown as spur gears may comprise any appropriate gearing 40 for accomplishing the result intended, and it is important to note that the gear ratio is preferably such as to afford a substantial leverage to enable easy actuation and control of the crank arm or plate 24. To this end, 45 also, a worm may be provided for the shaft 20 arranged to actuate a worm gear for actuating shaft 16, whereby a very substantial leverage will be provided, and at the same time the arm or plate 24 may be held at any 50 given position without the presence of the operator, the worm gear acting as a lock to retain the parts against movement when not operated by manual or other power. A form of worm gear connection is illustrated in 55 Figure 5 in which shaft 16 is shown as provided with a beveled gear 18' meshing with a beveled gear 19' fixed to a counter shaft 58 journaled in housing 22'. Worm gear 59 is fixed to shaft 58 and meshes with the worm 60 carried by the shaft 20' corresponding to shaft 20, and provided with an operating handle, crank, lever, or other power means, not illustrated.

It is, of course, well understood that excessive heat of quenching liquid is undesirable

and at times pronouncedly detrimental. To insure low temperature of the quenching liquid in quenching vat 32, I preferably provide for circulation by constantly introducing fresh quenching liquid through a supply pipe 61 and discharging heated liquid through a drain pipe 62. A valve 63 is preferably employed in the drain pipe to control the outflow relative and proportional to the inflow through pipe 61. When water is employed 70 as the quenching fluid, the pipe 61 will lead from the city water supply and the pipe 62 will lead to the sewer, but if oil or other substantially valuable liquid be employed, the pipes 61 and 62 may be parts of a circulating 75 system including appropriate cooling means, not illustrated.

It will, of course, be understood that the thermocouple 13 is capable of being used in any acceptable manner, but I have found it 80 preferable to remove the same from the molten salt with each operation, and, with that in mind, the arm or plate 24 is formed with an aperture 13', and the hood 46 is also formed with an appropriate aperture through 85 which the thermocouple 13 is introduced and from which it is withdrawn. The thermocouple 13 is, of course, always withdrawn immediately preceding a discharging movement 90 of arm 24, and, as a matter of convenience, the thermocouple may be inserted through the opening 8 so that the part 9 will function as a bracket or supporting hanger for sustaining the thermocouple during discharge of the 95 work and until the fresh supply of work has been delivered to the basket after its return to the vat 11. And, thereupon, the thermocouple is reintroduced into said vat.

In this connection also, it should be noted 100 that the opening in the hood through which the thermocouple 13 is inserted is comparatively small and substantially closed by the insulating head through which the wires of circuit 14 extend, and, when preferred, a modified form of mounting may be utilized 105 for the thermocouple, as shown in Figure 8, in which the wall 46a is that of the hood and is provided with an appropriate, parti-globular socket 46b in which is mounted a bearing ball 110 13a carrying the thermocouple 13b corresponding in structure and function with thermocouple 13. An appropriate heat-insulating handle 13c is preferably provided for manual manipulation of the thermocouple 115 13b to enable the operator to swing the thermoresponsive resistance at the inner free end of the thermocouple to and from the required position in the furnace vat. Obviously, any of various forms of joints, including 120 a slot and slide connection, may be utilized to enable the required movement of the thermocouple without leaving an opening through the hood, but whatever construction is employed must provide for sufficient movement 125 130

to enable the thermocouple to be moved clear of the path of swing of the arm 24.

As best seen in Figure 6, the vestibule hood 51 is preferably of a width just sufficient to snugly accommodate the necessary movements of the plate or arm 34 and its connected parts, which has the effect of largely discouraging access of moisture splashed from the quenching vat into or toward the hood 46, and as a further precaution against such access of such moisture, I preferably extend the walls of the vestibule hood 51 within the hood 48 into a cowl or tunnel-like structure having the side walls 51' and the cover 51'' extended as far into the hood 48 as permissible while allowing the requisite swing of the door 52 incident to movements of the tray 33, the extent of the projection of the said cowl being best seen in dotted lines in Figure 1.

It should be understood that except for continuously operating furnaces, the contents of the vat 11 will solidify upon cooling down, as, when the plant is shut down over-night. It is best practice not to permit the work carrying basket 29 to remain in the vat 11 when the heat of the furnace has been turned off, and, therefore, when the plant is to be closed down for the night or otherwise temporarily shut down, the operating handles 26 are fastened in a position with the basket 29 elevated above the vat 11, and is not lowered again into the vat until the furnace has been started and the contents of the vat 11 has again become molten.

What is claimed is:—

1. In apparatus for case-hardening metal work, the combination, with a furnace and a vat located to be heated thereby, of a work carrier, a quenching vat disposed adjacent the work carrier, and means for shifting the work carrier from within the first-mentioned vat to a position above the quenching vat for delivering the work to the quenching vat at substantially the temperature of the contents of the first-mentioned vat.

2. In apparatus of the class described, the combination, with a furnace and a vat located to be heated thereby, of a shaft journaled at one side of the vat, an arm outstanding from the shaft, a work carrier sustained by the arm in position for extending into the vat, and means for rocking the shaft for swinging the arm sufficiently to move the work carrier from the vat to an inverted position beyond the vat.

3. In apparatus of the class described, the combination, with a furnace and a vat located to be heated thereby, of a shaft journaled at one side of the vat, an arm outstanding from the shaft, a work carrier sustained by the arm in position for extending into the vat, means for rocking the shaft for swinging the arm sufficiently to move the work carrier from the vat to an inverted position beyond the vat,

and a quenching vat located to receive work discharged from the work carrier when swung to said inverted position.

4. In apparatus of the class described, the combination, with a furnace and a vat located to be heated thereby, of a shaft journaled at one side of the vat, an arm outstanding from the shaft, a work carrier sustained by the arm in position for extending into the vat, means for rocking the shaft for swinging the arm sufficiently to move the work carrier from the vat to an inverted position beyond the vat, and a quenching vat located to receive work discharged from the work carrier when swung to said inverted position, the quenching vat being spaced relative to the first-mentioned vat to insure against splashing of liquid from the former to the latter.

5. In apparatus of the class described, the combination, with a furnace and a vat located to be heated thereby, of a shaft journaled at one side of the vat, an arm outstanding from the shaft, a work carrier sustained by the arm in position for extending into the vat, means for rocking the shaft for swinging the arm sufficiently to move the work carrier from the vat to an inverted position beyond the vat, and a quenching vat located to receive work discharged from the work carrier when swung to said inverted position, the quenching vat being spaced below the plane of the upper terminus of the first-mentioned vat.

6. In apparatus of the class described, the combination, with a furnace and a vat located to be heated thereby, of a shaft journaled at one side of the vat, an arm outstanding from the shaft, a work carrier sustained by the arm in position for extending into the vat, means for rocking the shaft for swinging the arm sufficiently to move the work carrier from the vat to an inverted position beyond the vat for discharging work from the work carrier, means completely enclosing the work carrier throughout its movement, and means for venting the enclosing means.

7. In apparatus of the class described, the combination, with a furnace and a vat located to be heated thereby, of a shaft journaled at one side of the vat, an arm outstanding from the shaft, a work carrier sustained by the arm in position for extending into the vat, means for rocking the shaft for swinging the arm sufficiently to move the work carrier from the vat to an inverted position beyond the vat for discharging work from the work carrier, a quenching vat beneath the place of such discharge, means enclosing the full travel of said work carrier, and means for venting said closing means.

8. In apparatus of the class described, the combination, with a furnace and a vat arranged to be heated thereby, of a work carrier, means for moving the work carrier to and from said vat and to and from a discharging position beyond the vat, and a quenching

vat disposed to receive the discharge from said work carrier and located to avoid splashing of liquid from the quenching vat to the first-mentioned vat.

5 9. In apparatus of the class described, the combination, with a furnace and a vat arranged to be heated thereby, of a work carrier, means for moving the work carrier to and from said vat and to and from a discharging position beyond the vat, and a quenching vat disposed to receive the discharge from said work carrier and located sufficiently below the plane of the upper terminus of the first-mentioned vat to prevent splashing of 15 liquid from the quenching vat to the first-mentioned vat.

10 10. In apparatus of the class described, the combination, with a furnace and a vat arranged to be heated thereby, of a work carrier, means for moving the work carrier to and from said vat and to and from a discharging position beyond the vat, a quenching vat disposed to receive the discharge from said work carrier, a hood enclosing the full travel 25 of the work carrier, and means for venting said hood.

11 11. In apparatus of the class described, the combination, with a furnace and a vat arranged to be heated thereby, of a work carrier, means for moving the work carrier to and from said vat and to and from a discharging position beyond the vat, a quenching vat disposed to receive the discharge from said work carrier, a hood enclosing the 35 complete travel of the work carrier and sealed relative to the vats for retaining fumes therefrom against escape, and means venting said hood.

12 12. In apparatus of the class described, the combination, with a furnace and a vat arranged to be heated thereby, of a work carrier, means for moving the work carrier to and from said vat and to and from a discharging position beyond the vat, a quenching vat disposed to receive the discharge from said work carrier, a hood sealed against the furnace and surrounding the vat thereof, a hood superimposed on and sealed against the quenching vat and upstanding therefrom, a sealed vestibule hood intercommunicating said hoods and with said hoods providing the space for the path of the work carrier, and means for venting said hoods.

13 13. In apparatus of the class described, the combination, with a furnace and a vat arranged to be heated thereby, of a work carrier, means for moving the work carrier to and from said vat and to and from a discharging position beyond the vat, a quenching vat disposed to receive the discharge from said work carrier, hooding means for sealing the vats and work carrier at all times against dissemination of fumes, 50 means for venting the hooding means, and

means for discharging work from the quenching vat.

14. In apparatus of the class described, the combination, with a furnace and a vat arranged to be heated thereby, of a work carrier, means for moving the work carrier to and from said vat and to and from a discharging position beyond the vat, a quenching vat disposed to receive the discharge from said work carrier, hooding means for sealing the vats and work carrier at all times against dissemination of fumes, 70 means for venting the hooding means, means for discharging work from the quenching vat, and an automatically closing door for 75 enabling discharge of work from the quenching vat.

15. In apparatus of the class described, the combination, with heat treating means for metal work, of a quenching vat adjacent thereto, hooding means for the heat treating means, and quenching vat, means for delivering work from the heat treating means to the vat within the hooding means, a tray within the vat for receiving work being quenched, 85 and means for moving the tray to a position for discharging quenched work beyond the vat.

16. In apparatus of the class described, the combination, with heat treating means for 95 metal work, of a quenching vat adjacent thereto, hooding means for the heat treating means and quenching vat, means for delivering work from the heat treating means to the vat within the hooding means, 100 a tray within the vat for receiving work being quenched, and means for moving the work receiving tray from the vat to a discharging position beyond the hooding means.

17. In apparatus of the class described, the combination, with heat treating means for metal work, of a quenching vat adjacent thereto, hooding means for the heat treating means and quenching vat, means for delivering work from the heat treating means to the vat within the hooding means, a tray within the vat for receiving work being quenched, means for moving the work receiving tray from the vat to a discharging position beyond the hooding means, and an automatically closing door for the hooding means 110 for enabling such movement of said tray.

18. In apparatus of the class described, the combination, with heat treating means 120 for metal work, of a quenching vat adjacent thereto, hooding means for the heat treating means and quenching vat, means for delivering work from the heat treating means to the vat within the hooding means, a tray within the vat for receiving work being quenched, means for moving the work receiving tray from the vat to a discharging position beyond the hooding means, 125 and a pivoted, pendent door for the hooding 130

means for enabling such movement of said tray.

19. In apparatus of the class described, the combination, with heat treating means for metal work, of a quenching vat adjacent thereto, hooding means for the heat treating means and quenching vat, means for delivering work from the heat treating means to the vat within the hooding means, 10 a tray within the vat for receiving work being quenched, a rock shaft fixed to said tray at one side of said vat, and means for oscillating said rock shaft for swinging the tray from the work-receiving position to the 15 discharging position and for returning the tray to the work-receiving position.

20. In apparatus of the class described, the combination, with heat treating means for metal work, of a quenching vat adjacent thereto, hooding means for the heat treating means, means for moving work from the heat treating means to a position discharging into the quenching vat, and a cowl snugly enclosing the path of movement 25 of the work moving means and extending from the hooding means toward the place of discharge into the quenching vat.

21. In apparatus of the class described, the combination, with heat treating means 30 for metal work, of a quenching vat adjacent thereto, hooding means for the heat treating means, means for moving work from the heat treating means to a position discharging into the quenching vat, a cowl 35 snugly enclosing the path of movement of the work moving means and extending from the hooding means toward the place of discharge into the quenching vat, and hooding means for the quenching vat enclosing a 40 portion of said cowl.

In testimony whereof I affix my signature.
HEYMAN ROSENBERG.
